UNITED STATES PATENT OFFICE

172,222

FACE POWDER BLENDING KIT

Eldon P. Coverdell, Dallas, Tex.

Application November 3, 1952, Serial No. 22,113

Term of patent 3½ years

(Cl. D86—10)

To all whom it may concern:

Be it known that I, Eldon P. Coverdell, a citizen of the United States of America, residing in the city of Dallas, in the county of Dallas, State of Texas, have invented a new, original, and ornamental Design for a Face Powder Blending Kit, of which the following is a specification, reference being had to the accompanying drawing, forming a part thereof.

Fig. 1 is a perspective view of a face powder blending kit, showing my new design;

Fig. 2 is a side elevational view thereof; and Fig. 3 is a bottom plan view of the same.

I claim:

The ornamental design for a face powder blending kit, substantially as shown.
